CLAIM

The ornamental design for a mobile phone case having a backup charging feature, as shown and described.

DESCRIPTION

FIG. 1 is a front-top-left perspective view of a mobile phone case having a backup charging feature showing our new design;

FIG. 2 is a rear-top-left perspective view of the mobile phone case having a backup charging feature;

FIG. 3 is a rear-bottom-right perspective view of the mobile phone case having a backup charging feature;

FIG. 4 is a front view of the mobile phone case having a backup charging feature;

FIG. 5 is a back view of the mobile phone case having a backup charging feature;

FIG. 6 is a left side view of the mobile phone case having a backup charging feature;

FIG. 7 is a right-side view of the mobile phone case having a backup charging feature;

FIG. 8 is a top view of the mobile phone case having a backup charging feature; and

FIG. 9 is a side view of the mobile phone case having a backup charging feature; and,

FIG. 10 is a side view of a slice of the mobile phone case having a backup charging feature taken at the recess at 10-10 in FIG. 9.

The broken lines in the drawings depict portions of the mobile phone case having a backup charging feature that form no part of the claimed design.

1 Claim, 7 Drawing Sheets
